UNITED STATES PATENT OFFICE.

DAVID WOLFSON, OF ATLANTA, GEORGIA.

TRUNK.

1,031,762.

Specification of Letters Patent.

Patented July 9, 1912.

Application filed March 28, 1912. Serial No. 686,939.

To all whom it may concern:

Be it known that I, DAVID WOLFSON, a citizen of the United States, residing at Atlanta, in the county of Fulton and State 5 of Georgia, have invented certain new and useful Improvements in Trunks; and I do hereby declare the following to be a full, clear, and exact description of the invention, such as will enable others skilled in 10 the art to which it appertains to make and use the same.

My invention relates to an improvement in trunks,—its object being to provide a simple and durable construction of trunk 15 in which large hats or similar articles may be securely packed and safely transported.

With this object in view the invention consists in certain features of construction and combinations of parts as will herein- 20 after be described and pointed out in the claims.

In the accompanying drawings, Figure 1 is a view in side elevation of my improvement; Fig. 2 is a view in perspective illustrating the cover in its open position, and Fig. 3 is a top plan view.

1 represents the body of the trunk which may be of any desired size and shape although it is preferably made with flattened 30 sides 2, 2, and with rounded ends 3, 3. The body may be made of vulcanized fiber board, or other suitable material, and is strengthened and stiffened vertically and horizontally by wooden cleats 4, which may be riveted 35 to the inner and outer sides of the trunk. To the inner opposite sides of the trunk and midway its length are riveted the sheet steel guideways 5, which serve to strengthen and stiffen the trunk body and 40 also as guides for the removable partition 6, which is preferably made of vulcanized fiber board, although it may be made of sheet metal, and has transverse flanges 7 secured to its opposite edges, which fit and slide 45 within the guideways 5.

8, 8 represent flexible partition sections, which may be made of vulcanized fiber or any other strong and flexible material, and are secured at their middle portions by rivets to the opposite sides of the removable 50

partition 6. The partition sections 8 are made of sufficient width to enable their sides to be curved inwardly within the trunk section their edges abutting against the cleats 9 secured to the inner surfaces of the body 55 of the trunk. Hence by the employment of the single removable partition 6, with its partition sections 8, 8, attached thereto, the interior space of the trunk body is subdivided into two receptacles each of which is 60 substantially circular in cross section, and within which large hats or other articles may be safely packed and transported.

The cover 10 is hinged to one side of the trunk body and is provided with a flange 11 65 which fits over the upper edge of the body and is secured to the latter by means of straps 12 or in any other desired manner.

Having fully described my invention what I claim as new and desire to secure by Letters Patent, is:—

1. A trunk comprising a body portion provided interiorly on diametrically opposite walls with guideways, a partition movable in said guideways and partition sections 75 permanently secured to said partition at opposite sides thereof, each partition section coöperating with the wall of the trunk at two points to form a compartment.

2. A trunk comprising a body portion 80 having curved ends, and provided interiorly on diametrically opposite walls with guideways, a removable partition having side edges movable in said guideways, and curved partition sections secured on opposite sides of 85 the partition and coöperating with the curved ends of the body portion to form approximately circular compartments.

3. A trunk comprising a body portion, a removable partition in said body portion, a flexible partition section secured on each side of said partition, and two cleats secured in the body between its center and each of its ends, the cleats of each pair being engaged by and forming abutments for 95 the respective ends of one of the flexible partition sections.

4. The combination with a trunk body having metal guideways riveted to its opposite sides, and a partition adapted to fit 100

and slide in said guideways, of flexible partition sections secured to the opposite sides of said partition and cleats fastened to the interior of the trunk body and adapted to engage both free edges of each of said flexible partition sections, substantially as set forth.

In testimony whereof, I have signed this specification in the presence of two subscribing witnesses.

DAVID WOLFSON.
